No. 853,963.

PATENTED MAY 21, 1907.

J. C. DAWSON & T. E. HEETER.
LOOSE LEAF BINDER.
APPLICATION FILED NOV. 15, 1906.

UNITED STATES PATENT OFFICE.

JAMES C. DAWSON, OF ST. LOUIS, AND THOMAS E. HEETER, OF MAPLEWOOD, MISSOURI, ASSIGNEES TO SIEBER & TRUSSELL MNFG. CO., A CORPORATION OF MISSOURI.

LOOSE-LEAF BINDER.

No. 853,963.

Specification of Letters Patent.

Patented May 21, 1907.

Application filed November 15, 1906. Serial No. 343,597.

To all whom it may concern:

Be it known that we, JAMES C. DAWSON, a resident of the city of St. Louis, State of Missouri, and THOMAS E. HEETER, a resident of Maplewood, county of St. Louis, and State of Missouri, citizens of the United States, have invented certain new and useful Improvements in Loose-Leaf Binders, of which the following is a specification, and which are illustrated in the accompanying drawings, forming a part thereof.

The invention relates to loose leaf binders in which there is provided between the covers of a book a plurality of pairs of mating sheet-receiving prongs mounted to swing in a plane transverse to the length of the book and curved to form filing rings or arches when closed.

In devices of this kind it is desirable that the parts should be light and strong, and that mechanism capable of transmitting great force should be provided for closing the filing arches and for locking the prongs in the closed position.

The object of the invention is to provide a loose leaf binder of simple and durable construction, and comprising improved mechanism for opening and closing the filing arches.

The invention is exemplified in the structure to be herein described, and illustrated in the accompanying drawings, in which—

Figure 1 is a plan view of the binder mechanism showing a detail of the covers to which it is attached; Figs. 2, 3 and 4 are sectional views on the lines 2—2, 3—3 and 4—4 of Fig. 1; and Fig. 5 is a detail perspective view showing a spring employed in the device.

The binder mechanism of a loose leaf book constructed according to the invention preferably includes a supporting structure comprising a pair of metal plates 10, 11, one of which, as the plate 10, is shown as being of substantially the same length as the covers 12 of the book. Preferably the plate 10 is bowed to conform to the shape of the back of the book, and is embedded within the material of the covering, as shown, being provided with ears 13, 14, which project upwardly therethrough.

The plate 11 is secured in position by means of the ears 13, 14, and as shown is longitudinally bowed upwardly to provide an elongated chamber 15 for the operating

mechanism. A plurality of filing rings or arches are provided for receiving the sheets to be bound, and as shown each comprises a pair of mating binding post members 16, 17. Each of the binding post members 16, 17, has rigidly mounted therein adjacent its inner end a transverse pivot rod 18, and through this rod is oscillatably secured to the plate 11, by means of lugs or ears 19 turned up on the body of the plate and surrounding the rod. The inner ends 20, 21, of the binding post members extend into the chamber 15 through apertures 22 in the plate 11.

Means are provided for engaging the inner ends of the binding post members to open and close the filing arches. For closing the arches as shown, a cam-piece 23 having cams 24 adapted to bear downwardly on the inner ends 20, 21, of the binding post members, and a thumb-piece 25 projecting beyond the end of the binder mechanism, is slidably mounted within the chamber 15, being held in place against the under surface of the plate 11 by means of a plurality of lugs 26.

For opening each of the filing arches, a spring, adapted to bear upwardly on the inner ends of the binding post members, is provided. As shown, this takes the form of a leaf spring 27, secured to the floor of the chamber 15 by means of lugs 28 turned up from the plate 10 and slotted for a portion of its length to provide three arms 29, 30, 31. Two of these arms, as 29 and 30, are preferably curved upwardly for engaging the inner ends of the binding post members, while the third arm, as 31, is curved downwardly to react upon the floor of the chamber coöperating with the arms 29, 30, the lugs 28 permitting some rocking movement of the spring plate.

In using the device the binding post members 16, 17, may be swung on their pivots to open and close the filing arches by shifting the cam-piece 23, the cams 24 engaging the inner ends of the binding post members to close the arches whenever the cam-piece is advanced, and the spring arms 29 and 30 serving to open the arches whenever the cams 24 are withdrawn from contact with the inner ends of the binding post members. The rounded form of cams 24 provides means for firmly locking the arches in a closed position, for when the cam-piece 23 has reached the limit of its forward movement the highest

portion of the cam has passed the point of contact with the inner ends of the binding post members.

As the cam-piece 23 is located between the inner ends of the binding post members and the cover of the housing or chamber 15, great force may be applied for closing the filing arches without danger of stripping the binding mechanism from the covers 12 or base plate 10.

We claim as our invention—

1. In a loose leaf binder, in combination, a longitudinally and upwardly bowed supporting plate, an openable arch comprising a pair of mating binding post members pivotally mounted in the plate at opposite sides of its crown, each of the posts having one end extending below the plate, and a cam-plate mounted within the bowed portion of the plate and reacting downwardly on the inner ends of the posts.

2. In a loose leaf binder, in combination, a longitudinally and upwardly bowed supporting plate, an openable arch comprising a pair of mating binding post members pivotally mounted in the plate at opposite sides of its crown, each of the posts having one end extending below the plate, a cam-plate mounted within the bowed portion of the plate and reacting downwardly on the inner ends of the posts, and a spring opposing the cam.

3. In a loose leaf binder, in combination, a slideway housing consisting of a base plate forming the floor of the housing and a longitudinally bowed plate secured thereto, and forming the side walls and cover of the housing, an openable filing arch comprising a pair of mating binding post members each pivotally mounted in a side wall of the housing and having one end extending into its interior, a spring reacting between the floor of the housing and the inner ends of the posts, and a cam-plate mounted on the cover of the housing and reacting downwardly on the inner ends of the posts.

4. In a loose leaf binder, in combination, a slideway housing, an openable arch comprising a pair of mating binding post members each pivotally mounted in a side wall of the housing and having one end extending into its interior, a spring reacting between the floor of the housing and the inner ends of the posts, and a cam-plate mounted on the cover of the housing and reacting downwardly on the inner ends of the posts.

5. In a loose leaf binder, in combination, a supporting member, a binding post member

movably mounted thereon, and a reciprocable cam having a rounded face engaging the post, the highest part of the cam being adapted to pass the point of contact with the post before reaching the limit of its movement in one direction.

6. In a loose leaf binder, in combination, a longitudinally and upwardly bowed supporting plate, an openable arch comprising a pair of mating binding post members pivotally mounted in the plate at opposite sides of its crown, each of the posts having one end extending below the plate, and a reciprocable cam mounted within the bowed portion of the plate and having a rounded face reacting downwardly on the inner ends of the posts, the highest part of the cam being adapted to pass the point of contact with the posts before reaching the limit of its movement in one direction.

7. In a loose leaf binder, in combination, a supporting member, an openable arch comprising a pair of mating binding post members pivotally mounted on the supporting member, means for closing the arch, and a three-part spring for opening the arch, one of its parts engaging each of the binding post members and the other part reacting upon the supporting member.

8. In a loose leaf binder, in combination, a supporting member, an openable arch comprising a pair of mating binding post members pivotally mounted on the supporting member, a leaf spring mounted on the supporting member and having three arms, two arms of the springs being bowed upwardly, one of such arms engaging each of the binding post members and the other arm of the spring being bowed downwardly and reacting upon the supporting member, and means for turning the binding post members in opposition to the spring.

9. In a loose leaf binder, in combination, a supporting member, a binding post member oscillatably mounted thereon, a divided leaf spring secured to the supporting member, one portion of the spring engaging the binding post member and another portion of the spring reacting upon the supporting member, and means for moving the binding post member in opposition to the spring.

JAMES C. DAWSON.
